United States Patent Office.

W. H. SULLENBERGER, OF HARRISBURG, PENNSYLVANIA.

Letters Patent No. 94,524, dated September 7, 1869; antedated August 25, 1869.

IMPROVEMENT IN COMBINED KNOB-LATCH AND LOCK.

The Schedule referred to in these Letters Patent and making part of the same.

To all whom it may concern:

Be it known that I, W. H. SULLENBERGER, of Harrisburg, county of Dauphin, and State of Pennsylvania, have invented a new and improved Latch-Lock; and I do hereby declare that the following is a full, clear, and exact description of the construction and operation of the same, reference being had to the annexed drawings, making a part of this specification, in which—

Figure 1 is a plan of the lock, locked.

Figure 2 is a plan of the lock, partially unlocked.

Figure 3 is a plan of the lock unlocked, and, as such, answering a knob-latch.

Figure 4 is a plan of the escutcheon lever.

Figure 5 is a sectional view of the bit of the key.

Figure 6 is a side view of the reversible keeper.

Figure 7 is an end view of the lock-case.

I construct my lock, as hereinafter explained, to act as a dead-latch, as a common knob-latch, and as a lock, and in such form of the case and the keeper as to be applicable to a right or left-hand door, externally, or as a mortise lock.

The working parts consist of an arbor, a slide and its thumb-piece, an escutcheon, attached to a lever, and a bolt, all arranged in a case which has certain stops, pins, and guards, to locate and regulate these parts.

The arbor has the usual cylindrical journals for bearings in the sides of the case, and for the attachment of knobs.

Attached to the arbor is a lug, *b*, which is so situated as to strike a stop, *B*, when the arbor is rotated backward, and is of such length as to pass free of the walls of the case when the arbor is rotated forward.

Nearly opposite said lug *b*, on the front side of the arbor, are projections, *a* and *a'*.

The projection *a'* serves as an additional stop against the wall of the case, acting simultaneously with the lug *b*, when the arbor is rotated backward; and the projection *a* serves as a stop against the stop *B* when the arbor is rotated forward.

The recess *d*, between said projections, receives the end *S* of the slide tightly, and the arm *C* of the lever loosely.

Said slide *S S'* rides on a track, *Z*, fig. 3, has a lug on its under side which fills the space, transversely, between the rail *Z* and the side of the case, and is of such thickness as to come flush with the face-plate when it is in place on its track.

It has a recess, *S'*, on one side for the insertion of the double-headed thumb-piece *T*, as shown in fig. 1. Said thumb-piece is so made as to keep in its place when the face-plate is on the case.

It will be observed, that when the slide is shifted and the end *S* is in the recess *d*, the arbor can be rotated neither forward nor backward, and, as herein-

after explained, when this is the case, the latch-bolt cannot be lifted. It is therefore a dead-latch.

The escutcheon-lever, *C H E E'*, fig. 4, has three main working-points, an arm, *C*, a heel, *H*, and a curved toe, *E E'*, and is pivoted at *D* by a pin in the lock-case, as shown in figs. 1, 2, and 3.

The end of arm *C* is narrow enough to enter the recess *d* loosely, and to play in it when the arbor is rotated, as shown in fig. 3, thus vibrating about its pivot *D*, while the pin *F*, on its heel *H*, acts as a trip-lever for the latch *V*.

Said arm *C* is cut obliquely at its end to receive the projection *a'*, about midway on its end, when it is thrown up and out of recess *d*, as shown in fig. 1. The arm is always thus elevated when the bolt is thrown forward, and when thus elevated it can go no further up, as the toe *E'* abuts against a stop, *J*, as shown in fig. 1. The arbor then cannot rotate forward or backward, as it is stopped at *b*, *a'*, and *C*, therefore the lock cannot be unlocked except with a key, because projection *a'* cannot be depressed over the oblique end of *C*, but said end can be depressed beneath projection *a'*, and only by the action of the key, as hereinafter explained.

The latch-bolt *V*, figs. 1 and 3, has near its centre two recesses, *3 4*, which form bearings for the pin *F* on the heel *H* of the escutcheon lever. Said recesses *3 4* run into each other in a wave line or stair, the recess *3* being lower than *4*, and to the rear of it; thus two recesses are made for said pin *F*, with a path for it to traverse from the one to the other.

The recess *4* has an arch, *5*, over it, which serves as a hook by means of which the pin *F* lifts the latch, as shown in fig. 3, when said lever is tripped by arbor *A*.

The pin *F*, when it is midway between the recesses *3 4*, as shown in fig. 2, impinges against the end of the hook *5*, and thus assists in lifting the rear or weighted end *W* of the latch. Said end *W* is thus sufficiently raised to free the tooth *7* from pin *m*, on the lower side of the latch, while a guard, *O*, and a tooth, *p*, on the upper side of the latch, regulate the throw, so that no violent action in the process of locking or unlocking or latching, can throw the latch-bolt out of working connection. Further, the bit *L* of the key, fig. 2, in the act of locking and unlocking, by contact with a tooth, *9*, likewise raises the weighted end *W* of the latch-bolt, so that the pin *F* on the lever, and the said bit *L* of the key, have a joint and simultaneous action to pass the latch-bolt from notch *1* to notch *2*, over the pin *m*, and *vice versa*, the escutcheon *E'* standing against the shank of the key while it completes its revolution, and thus holding the pin *F* poised to find its path from one recess to the other.

The pin *F* is elliptical in form, and is so placed that its lower sharp side, when in recess *3*, resists firmly

the return of the bolt into the case, as shown in fig. 1, unless it is returned with the key.

When the latch-bolt is locked, as shown in fig. 1, the pin *m* is in notch 1; the pin *F* is in recess 3; the arm *C* is against the projection *a*; the key-hole *K* is open, and the bolt *V* is thrown full into the keeper, under the pin *P*.

It will be observed that the arbor *A*, as already explained, cannot now be rotated, the head of bolt *V* cannot be lifted, and the pin *F* cannot be disengaged from the recess 3 without the aid of the key; the lock is therefore locked.

No ordinary key will unlock this lock from the nature of the turn which it must make in the escutcheon *E E'*.

From the position of insertion of the key, as shown in fig. 1, the escutcheon and bit of the key pass to the position shown in fig. 4.

The curved toe *E'* cuts or dips into the recessed bit *L*, while the outer end of the bit tightly hugs a projection, *n*, on the escutcheon, which point must be passed before the key can be sufficiently rotated to actuate the bolt, as shown in fig. 2, and the key-shank must also be sufficiently thick to keep the escutcheon in the propped or suspended position, as shown in fig. 2, in order to free the pin *F* from recess 3 in the bolt, as well as to release the arbor. The key is therefore made, as shown in fig. 5, with straight or full outline of the bit, except that its sides are recessed to such an extent as to leave only a thin parting of metal in the body of the bit. If an ordinary serrated key-bit is thus cut to fit this lock by burglars or others, there will not be sufficient strength left in the bit to effect unlocking.

When, as shown in fig. 3, the pin *m* is in notch 2, the pin *F* in recess 4, the arm *C* in recess *d*, and bolt *V* is withdrawn from its keeper, *R*, the lock is unlocked, and it then acts as a latch, for the arm *C* is free to play in recess *d*, while arbor *A* is rotated, and this action of the lever trips the lever on its pivot *D*, and thus the bolt *V* is lifted, its weighted end *W*, in connection with the guard *o*, keeping it in position on the pin *m*. The escutcheon lever in this position partially shuts the key-hole *K*, so that if now the slide *S* be

shifted so as to lock the arbor, the latch cannot be lifted from without, as the pin *F* resists the ascent of it, and the ascent of the pin *F* itself is resisted by the arbor, which, by this condition, is locked, therefore no key can be inserted outside, and this is a dead-latch and lock combined. The slide *S* may also be thus combined with the arbor when the bolt is thrown forward while the key is in the lock, as shown in fig. 1, and the key itself will thus be locked fast to close the key-hole against burglars.

The keeper *R*, as shown in figs. 1 and 6, is reversible, having two heads, *M N*, with screw seats, and has right and left abutments, *Q*, which are so rounded as to serve as strikes for the latch. Viewed, as in fig. 6, the keeper is so recessed that after the latch has passed the strike *Q*, it falls into a recess, and that if now the latch is thrown forward, as in fig. 1, it is held under the pin *P*. It can thus be lifted out of the recess only after the act of unlocking.

The front end of the lock, as shown in fig. 7, has two flanges, one on each side of the case, whose outlines match the curvature of the keeper nearly, so that the lock can be applied to a right or left-hand door, or by mortising the door and its jamb, it may be used as a mortise lock.

I disclaim certain arbors with side projections, lugs, pins, or their equivalents; neither do I claim, broadly, the use of double or reversible keepers; but

What I do claim as new, and what I desire to secure by Letters Patent of the United States, is—

1. The escutcheon lever *C H E E'*, when pivoted at *D* and made to vibrate between the projections *a a'*, substantially as, and for the purpose herein set forth.
2. The latch *V*, provided with recesses 3 4, notches 1 2, and tooth *p*, in combination with lug *F*, pin *m*, and guard *o*, all arranged to operate substantially as and for the purpose set forth.
3. The escutcheon *E E' n* of the lever *C H*, in combination with key-bit *L*, arranged to operate substantially as and for the purpose set forth.

W. H. SULLENBERGER.
